CARRIAGE TABULATING MECHANISM SUITABLE FOR PROPORTIONAL SPACING TYPEWRITER

John Toggenburger, Hartford, Conn., assignor to Underwood Corporation, New York, N.Y., a corporation of Delaware

Filed Apr. 7, 1955, Ser. No. 499,791

26 Claims. (Cl. 197—176)

This invention relates to carriage tabulating devices in general and more particularly to such devices used in association with proportional letter-feeding mechanisms.

In machines having proportional letter-feeding mechanisms, a carriage is usually fed in multiples of fine, definite feeding increments. Therefore, the position of the carriage varies in accord with these fine feeding increments. Great difficulties are encountered in constructing a tabulating mechanism to bring the carriage at tabulations to rest in the specific intended, fine incremental feed position. Much of this difficulty arises from the fact that the carriage rebounds at interception, wherefore the escapement is apt to gain control over the carriage one or more feeding increments from the intended tabulating position. Even disregarding the rebounding, manufacturing tolerances of parts of the escapement mechanism, the tabulating mechanism, etc., make it difficult for the escapement to assume accurate incremental control at the end of the tabulation.

According to the invention the tabulating arrest of the carriage is effected by the projection of a stop element automatically into engagement with a coarsely-toothed member or wheel. This occurs as the carriage nears the conclusion of each tabulating run. The coarsely-toothed member or wheel has rugged teeth at intervals corresponding to a specific multiple of the small feed increment. The stop element is also rugged and is projected into the coarsely-toothed member in response to the tabulating travel of a tabulation-terminating control element against a related element on the frame, the latter being projectable into range of said control element by operation of a tabulating key or control.

At the end of a tabulating run, substantially incidental to the projection of the stated stop element, a cyclic operating device is rendered active and after a time interval sufficient for the carriage to come accurately to rest, is effective to place the carriage first under the control of the letter-feeding mechanism and then to withdraw the stated projected stop element. In this manner the carriage is tabulated accurately to the intended incremental feed position.

It is thus accordingly an object of the invention to provide a tabulating mechanism which functions accurately and reliably under all operating conditions and situations.

It is an object of the invention also to provide in efficient cooperative association with a reliably operative and simple proportional letter-feeding mechanism, a tabulating mechanism functioning to arrest the carriage accurately and reliably.

A further object of the invention is to provide a tabulating mechanism which is rugged, reliable in operation, and needs no delicate adjustments.

A further object of the invention is to intercept the carriage in its tabulating runs by the projection of a stop into movement-terminating engagement with a toothed member or wheel, the teeth of such member being spaced in accord with a certain multiple of a feed increment.

It is also an object of the invention to provide a rugged

2

mechanism to terminate tabulations, such mechanism being brought into action automatically at the approach of the end of a tabulating run by the displacement of one element by another, one such element being on the carriage and the other on the frame.

5 A further object is to provide in combination with a series of key-settable tabulation-terminating control elements arranged at intervals in accord with a multiple of a feed increment, a member having teeth arranged in accord with said intervals and a stop movable into tabulation-terminating engagement with said member under control of a set controlling element by carriage movement.

10 It is a still further object of the invention to provide in a proportional spacing typewriter having a row of key-settable tabulation-terminating control elements, an element projectable into cooperative range with set ones of said control elements in a resilient manner and preferably capable of temporary deflection if at projection thereof it happens to clash with one of the said control elements.

15 Still other objects and features of the invention will be apparent from the detailed description which follows as such description is read in the light of the accompanying drawings.

20 25 It will be appreciated that the invention is correlated with various other features and mechanisms to produce a practical machine comparable in efficiency with machines having conventional uniform letter-feeding mechanism. To the end of facilitating a more complete understanding 30 of the ramifying problems involved in connection with the invention, the present disclosure reaches in many respects beyond the actual subject matter claimed.

25 Referring now to the drawings, Figure 1 is a right-hand sectional side view of the machine, showing portions of a proportional letter-feeding mechanism, a tabulating mechanism and a carriage-returning mechanism, the section being taken generally through the middle of the machine.

30 Figure 2 is a fragmentary plan view of some of the mechanism seen in Figure 1.

35 Figure 3 is a detail view of a space-controlling stop and its manner of support.

40 Figure 4 is a fragmentary plan view of a single increment back-spacing mechanism.

45 Figure 5 is a right-hand sectional side view of certain parts of a mechanism whereby the machine can be set for normal or widened proportional spacing.

Figure 6 is a front sectional view of the machine.

46 Figure 7 is a diagram of circuitry and related parts 50 whereby electric magnets are controlled.

Figure 8 is a right-hand front perspective view illustrating several space keys with associated mechanism.

55 Figure 9 is a right-hand sectional side view illustrating a power actuating device for the tabulating mechanism.

Figure 10 is a fragmentary perspective view depicting a wheel and a cam-roll connectable thereto to receive single turns.

Figure 11 is a right-hand front perspective view of a power return mechanism for a carriage.

60 Figure 12 is a front view of a portion of the tabulating mechanism, including a projectable control element, the mechanism being in a normal state.

65 Figures 13 and 14 are similar to Figure 12 but the projectable element has been projected ultimately to function in causing the termination of the tabulating run.

70 Figure 15 shows a fragment of the proportional spacing mechanism, along with a pawl for action on a coarsely-toothed wheel, for back-spacing the carriage to positions variant in accord with a certain multiple of a feed increment, all parts being in their normal positions.

75 Figure 16 is similar to Figure 15 but the back-spacing pawl is shown approaching fully operated position.

In Figures 17 and 19 the coarsely toothed wheel of Figure 15 has different incremental positions, but is rotatable by the back-space pawl to identical coarse-tooth positions.

Figure 18 is a fragmentary showing of a device active at tabulations and carriage returns to arrest the carriage in positions variant in accord with a certain multiple of a feed increment.

Figure 19 is a right-hand side view of the back-spacing mechanism shown in Figure 15, along with a power actuating mechanism therefor.

Figure 20 is a plan view showing an escapement dog operated to the limit of an abutment for producing normal proportional spacing and showing control mechanism in a condition whereby in the next escapement operation said escapement dog is limited by another abutment for producing more open proportional spacing.

Figure 21 is similar to Figure 20 but the mechanism is conditioned for open proportional spacing.

Figure 22 is a sectional side view illustrating a mechanism for arrest of the carriage at tabulations, the mechanism being shown in the process of movement to an inactive position.

Figure 23 is a fractional plan view of certain parts related to carriage interception at tabulations and carriage returns, the parts having been conditioned by an institution of a carriage return operation to be responsive to the last part of the return movement of the carriage to effect the interception thereof.

Figure 24 is a perspective illustration of a space controlling stop.

Figure 25 shows a variably conditionable stop mechanism of the proportional spacing mechanism.

Finally, Figure 26 is a plan view showing the spacing dog of the proportional spacing mechanism actuated free of the escapement wheel and another dog temporarily halting the carriage by co-action with another wheel.

Referring now more particularly to Figure 1 the invention is shown embodied in an Underwood all-electric typewriter which embodies a power typing mechanism of the kind shown in the patent to Yeager, No. 2,254,764, dated September 2, 1941. Said typing mechanism includes a complement of type bars 10 individually swingable on a segment 21, about a common fulcrum rod 12, to type at a common typing point against a platen 11. Each type bar 10 is power operable by an actuator 13 through a train of mechanism comprising a generally upright sub-lever 14, there being a transverse row of said actuators 13 and a transverse row of said sub-levers 14. All said actuators 13 are normally spring-held clear above a toothed power roll 15 and are adapted to be lowered into motion-receiving intermesh with said power roll, the latter rotating constantly in the direction of the indicated arrow when the machine is in use. Key levers 16 having keys 22, one for every actuator 13, are individually operable to connect the actuators 13 selectively with the power roll 15 for single transitory operations, thereby to cause operations of the type bars 10 selectively. Springs 17, 18 and 20 bias the parts of each type action toward their normal positions shown in Figure 1.

A frame structure of the machine comprises two laterally spaced side walls 23 rigidly connected by a bar 19 which includes a pivot rod for the key levers 16. Said side walls 23 are also rigidly connected by a transverse trackway 24 whereon a carriage 25 is guided for travel in letter-feed and return directions, the said carriage having turnably supported thereon the aforesaid platen 11. For carriage guiding cooperation in the trackway 24, the carriage 25 includes a channel bar 26, usual anti-friction elements 27 being provided between the trackway 24 and said channel bar 26. The carriage 25 is constantly urged in letter-feed direction, that is leftwardly, by a spring motor which is indicated at 28 and has a draw-band connection 30 with the carriage 25. However, advance movement of the carriage is subject to the control of a

proportional letter-feed mechanism which will be described hereinafter.

The type bar segment is normally in a lower case typing position seen in Figure 1, for the lower case types "t" to strike the platen. A case shift body 31 supports said segment 21 for vertical downward shift from said lower case position to an upper case typing position wherein upper case types "T" are adapted to strike the platen. The mechanism for effecting such case shift of said body 31 is fully described in the patent to Hellmond, No. 2,275,759, dated March 10, 1942, and includes a case shift key 29 indicated in Figure 8. The case shift body 31 has near each side wall a stud 31a, and a transverse bail 39, indicated in Figure 7, is pivotally supported by the side walls 23 of the machine and associated with said studs to enforce concomitant movement of both ends of the case-shift body. Case shift motion is imparted by a power member, not shown, to a rocker 52 which flanks the right side wall of the machine and straddles the stud 31a thereat. The full line position of the rocker 52 is the lower case position. The upper case position is indicated by dot-and-dash lines.

Advance travel of the carriage ensues under control of an escapement dog 32 which is normally in engagement with an escapement wheel 33, the latter being unitarily rotatable with a shaft 34 which at its upper end has a pinion 35 meshing with a rack 36 carried fast on the channel bar 26 and extending parallel therewith. The trackway 24 has a boss 37 providing an upper bearing for the shaft 34. A lower bearing for said shaft is provided in a generally horizontal escapement bracket 38 having two spaced, upturned ears 40 for securing by screws to downreaching arms 41 of the trackway 24. The said escapement wheel 33 is in the form of a ring, see Figure 1, and is secured by rivets or otherwise to a companion escapement wheel 42, the latter having a hub 43 pinned fast to the shaft 34. The stated escapement dog 32 is borne pivotally, as at 44, on an arm 45 which is swingable concentrically about a lower end portion of the shaft 34, said arm 45 having a broad pivotal bearing or collar reaching upwardly into the general plane of the wheel 33. The urge of the spring motor 28 tends to turn the escapement wheel 33 constantly in the direction of the arrow seen in Figure 2, and because the escapement dog 32 is normally engaged in the wheel 33, a branch 46 of the supporting arm 45 rests normally limitedly against an abutment 47 afforded by an arm 48. The latter is normally stationary on a pivot stud 50 which in turn is carried fast on the bottom side of the bracket 38.

Letter-feed travel of the carriage is to be substantially proportional to the widths of the imprints in terms of different multiples of a given feed increment. The spacing of the escapement teeth on the wheel 33 is in accord with the stated feed increments, considered however in the aspect of translation of carriage movement into wheel movement.

Incidental to each operation of a type action the carriage 25 is required to advance substantially proportionally to the widths of the characters typed in terms of the said feed increments. To this end, at each operation of a type action, the feed dog 32 is released temporarily from the escapement wheel 33 and under the influence of a spring 55 is caused to take up a new tooth-hold in the wheel an appropriate number of escapement wheel teeth away from the abutment 47 so that the carriage then is controlled to advance the required number of feed increments. As the carriage, following such re-association of the dog 32 with the wheel, turns the escapement wheel 33 counterclockwise of Figure 2, the arm 45 moves limitedly against the abutment 47.

The lower-case types and upper-case types of almost half the number of type actions, namely twenty-one type actions, call respectively for three-increments and four-increments feed of the carriage. Having reference to

Figure 2, there stands clockwise of a finger 56 which is integral with said dog, a stop arm 49 on a pivot stud 57, the said stop arm having two stop faces 53 and 54. The second digits of the numerals designating these stop faces 53 and 54 signify that such faces are instrumental to effect reengagement of the feed dog 32 respectively for controlling a three and four tooth advance of the wheel 33. The case shift body 31 has control over the arm 49 so that when it is in lower-case position, the said arm 49 has the position seen in Figure 2, wherein the stop face 53 stands in the path of said finger 56. The case shift body 31 controls the position of the stop arm 49 through an element 58 which is pivotally pendant therefrom and has at its lower end a cam 59 resting leftwardly against a pin 51 which projects rearwardly from the crossbar 19 of the machine. A wire link 60 connects said stop arm 49 with the element 58 and the cam 59 rests leftwardly against the pin 51 under the tension of a contractile spring 52 connected to the stop arm 49 and having a leftward and upward bias thereon. In the lower case position of the said body 31 the said element 58, controlled by the said cam 59 resting leftwardly against said pin 51, has the position shown in Figure 6, locating the stop arm 49 so that its stop face 53 is potentially effective, see Figure 2. Whenever the body 31 is shifted downwardly to the upper-case position, the said element 58 is cammed rightwardly and through the link 60 positions the stop arm 49 so that its stop face 54 stands in the path of the dog finger 56.

Normally out of use, clear above the level of the arm branch 46 and the dog finger 56, there are arranged in a row, concentrically about the escapement wheel shaft 34, a series of stop pins numbered 61 to 65 inclusive. The second digits of these numerals 61 to 65 are indicative of the incremental carriage advance which each such pin is adapted to determine by effecting varyingly the re-association of the dog 32 with the escapement wheel 33 after different clockwise movements. The said pins 61 to 65 are guided for vertical movement in the horizontal bracket plate 38 and a plate 70 which is in a parallel plane therebelow, see Figures 6 and 25. The said pins stand normally upwardly restored, out of cooperative range with said dog finger 56, springs 71 being provided on the pins, to act upwardly on collars causing them to bear upwardly against the horizontal plate 38. The lower end of the pin 63 is preferably broadened radially of the escapement shaft 34, as indicated in Figures 2 and 3, so that such pin will always overlie the stop arm 49. The stop pin 65, see Figure 25, is slightly longer than the others and the stop arm 49 bears upwardly thereagainst under the urge of a spring 52. Having specific reference to Figures 24 and 25, it will be noted that the stop arm 49 is formed with top and bottom nodes 73 at opposite sides of the pivot stud 57, which nodes are so arranged that the stop arm 49 is capable of downward swinging displacement flatwise to an idle position indicated by dot-and-dash lines in Figure 25, it being understood that the arm 49 is somewhat loosely pivoted on the stud 57. Any of the pins 61 to 65 when operated is adapted to limit clockwise movement of the escapement dog 32. At operation of any of the pins 63 to 65 the stop arm 49 is pushed downwardly about the general location of the nodes 73 to have no controlling effect on the dog 32. Obviously the link 60 permits freely the stated downward displacement of the stop arm 49.

The several pins 61 to 65 remain in their idle, normal positions whenever any type action is operated which for lower case and upper case typing requires respectively a three and a four increments feed step of the carriage. Therefore, at operations of such type actions, either the stop face 53 or the stop face 54 stands in the path of the dog finger 56, depending on the prevalent case shift position of the case shift body 31. At operations of other type actions which in at least one case shift position of

5 said body 31 require a feed step of a different incremental value, and thus a different clockwise travel of the escapement dog 32, the pins 62 to 65 are selectively operated by electromechanical means in a manner which will be explained later herein.

At the operation of any type action the operated type bar 10 displaces a curved universal bar 76 rearwardly, such universal bar, see Figures 1 and 6, having pivotal connections at 77 with a rocker frame 78, the latter including a short shaft 80 and an arm 81 pendant from such shaft. The rocker frame is pivotally supported, as at 83, on arms 82 which are part of the case shift body 31. The rocker 78, influenced by a spring 84, has normally the position seen in Figure 1. In front of the 10 rocker arm 81 is a lever 85, pivotally borne on a stud 86 which is carried fast on the underside of the escapement bracket plate 38. A right arm of said lever 85 has an open mouth 87 straddling a pin projecting from the dog 32, see Figures 2, 20 and 21. A spring 88 connected to 15 the left arm of the lever 85 is normally instrumental to hold the dog 32 engaged in the escapement wheel 33. At operation of any type action the universal bar 76 is operated rearwardly, causing a forward operation of the pendant rocker arm 81. This rocks the lever 85 counter-clockwise of Figure 2 and turns the dog 32 on the arm 45 to stand clear of the escapement wheel 33, the dog finger moving concomitantly from the arm branch 46. Furthermore, the dog supporting arm 45 being under the 20 constant urge of the spring 55 immediately moves circumferentially of the wheel 33, clockwise until the dog finger 56 rides limitedly into engagement with one of the stop faces 53 or 54, or one of the stop pins 62 to 65. During this clockwise sweep of the dog 32 the pin on 25 the latter rides out of the mouth 87 but the dog 32 is maintained clear of the escapement wheel 33 under the influence of a spring 90, see Figure 2.

If the operated type action is one of the twenty-one which require a three or four increments feed respectively for typing in lower and upper case, then the dog finger 30 56 will engage either the face 53 or the face 54 on the stop arm 49 depending on whether such type actions are operated with the body 31 in lower case position or upper case position. As the dog finger 56 encounters the face 53 or 54, the dog supporting arm 45 travels farther and this forces the dog 32 about its pivot 44 into mesh with the wheel 33, the dog finger 56 under tension of the spring 55 lying finally solidly between the engaged stop face and the arm branch 46. The stated circumferential movement of the dog 32 and re-engagement with the 35 wheel 33 conditions the dog 32 for measuring out to the carriage the appropriate multiple-increment feed step. Said circumferential movement occurs while the carriage, due to its inertia, stands momentarily stationary. After the inertia of the carriage has been overcome, the 40 wheel 33 under the urge of the spring motor 28 moves counter-clockwise and carries the dog therewith until the abutment 47 intercepts the arm branch 46, the carriage having then reached its required incremental feed position. The teeth of the escapement wheel 33 are slightly undercut and the dog 32 correspondingly formed so that during the feed step the said dog is maintained in engagement despite the disengaging bias of the spring 90. It is to be understood that the operation of the universal 45 bar 76 is momentary and that the lever 85 restores before the carriage completes its letter-feed step, wherefore the dog pin will enter appropriately the mouth 87 in the lever 85. The lever 85 under the tension of the spring 88 is then effective to maintain the dog 32 engaged.

The several stop pins 62 to 65 inclusive are operable 50 severally by electromagnets 92 to 95, inclusive, see Figures 2, 6 and 7. Said electromagnets are suitably supported by a plate 96 which is fastened upon a series of studs 97, the latter projecting upwardly from the escapement bracket 38 and being of rectangular cross-section. Said studs 97 have reduced screw portions 98 extending

through the escapement bracket 38 and the underlying plate 70. On the said screw portions 98, between the plate 70 and the escapement bracket 38, there are spacers 100. Nuts 101 on said screw portions hold the studs, the plate 70 and the escapement bracket 38 rigidly united as shown in Figure 6. The several studs 97 have each on one side pivotally supported thereon a lever 102 comprising an arm having an armature 103 for attraction by the core of the related magnet. Each lever 102 comprises another arm overlying a related stop pin 62, 63, 64 or 65. Any of the several magnets, when energized, will attract its related armature and thus will operate its associated lever 102 and thereby set its related stop pin.

Such of the type actions which either for lower case or upper case typing require a feed-step different from that obtainable under control of the stop arm 49 are adapted in their actuation to effect closure of a related pair of contacts 107 and 108, see Figures 1 and 7. Such type actions have each a wire link 110 articulated with a downwardly and rearwardly reaching arm of the sub-lever 14. Each of said links 110 is downreaching between the key levers 16 and therebelow is pivotally connected to an arm 111 which has pivotal support on an ear 112, the latter being bent rearwardly from a comb plate 113 guiding the key levers 16. The said arms 111 have washers 114 of insulating material for individually actuating the contacts 107 upwardly. The type bars 10 commence to operate the curved universal bar 76 approximately when they reach the dot-and-dash position indicated in Figure 1. The said washers 114 stand normally well below the contacts 107 and effect contact closure about when the type bars 10 reach the stated dot-and-dash position.

Referring now to the electrical diagram of Figure 7, there are shown a series of the type keys 22 which severally are representative of different type actions. The type key 22 shown at the extreme right in said figure, represents one of the twenty-one type actions which in their operations do not involve the magnets 92 and 95. The lower and upper numbers on these keys signify that respectively in the lower and upper case position an operation of one of these keys will result in the incremental feed indicated respectively by the lower and the upper numbers. The other type keys 22 in the said diagram have noted thereon lower and upper numbers indicative of the incremental value of the letter-feed steps which result respectively at the lower and the upper case typing operations thereof. It will be noted that the numbers on these type keys are of differing combinations and at least one of the numbers disagrees with respect to the rightmost illustrated type key 22. Below each of the keys 22, except the rightmost illustrated one, there is a diagrammatic representation of a pair of the stated contacts 107 and 108. The aforescribed type-action-operable arms 111 are indicated in dot-and-dash lines. The written notations above the keys show how many of each of said keys calling for the same letter-feed control are present in the machine. Of course, the requirements vary in accord with the particular type font embodied in the machine. In reference to the numbers noted on the type keys 22, those which are in solid lines signify that an electromagnet is involved for letter-feed control, and those which are in dotted lines signify no involvement of an electromagnet. The type action controlled by the key 22 which has two "2" notations above each other will, responsive to any operation of such key, by closure of its related contacts 107, 108, always close a circuit for the magnet 92. This is whether typing occurs in lower or upper case. The circuit so closed comprises a lead 117 from a current supply plug 118 to the contact 107 of the pertinent type action, and a lead 120 from the related contact 108, merging with a lead 142 to the magnet 92. The magnets 92 to 95 have a common lead 124 to the current supply plug 118.

The type action controlled by the key 22 which has

two "3" notations will, responsive to any operation of such key, close its related contacts 107, 108 and thereby will always complete a circuit for the magnet 95. Such circuit comprises the lead 117 from the plug 118 to the contact 108 of such type action, and further a lead 119 from the related contact 107 merging with a lead 145 of the magnet 95.

From the contacts 107 associated with the other keys 22 there extend parallel circuit leads 126^a to 126^c, inclusive, variously to switch fingers 127. Said switch fingers comprise part of a case-shift controlled electrical switching means generally designated by the numeral 128 and including other switch fingers 129 interspersed with the switch fingers 127. The switch fingers 129 are longer and reach into notches provided in a link 130 of insulating material. The switch fingers 127 and 129 are mounted insulated from each other in an insulating block 131 which is carried fast on the left side wall 23 of the machine. A lever 132 having a follower roll 133 bearing on a two-step cam formation 134 provided on the case-shift rocker 52, controls the position of the link 130 so that in the lower case position of the case-shift body 31 it has the full-line position, and so that in the upper case position of said body it has the position indicated in dot-and-dash lines, flexing the contact fingers 129. One end of the link 130 is slotted for sliding support on a pin 135 that projects from the side wall 23. A strong spring 136 causes the roll 133 to bear on the cam 134.

The circuitry is such that in the lower-case state of the switching means 128 certain of said fingers 127 have contact with certain of the fingers 129 so that the leads 126^b and 126^c are normally in circuit with the leads 142 to the magnet 92, and also so that leads 126^a and 126^c are normally in circuit with the lead 144 to the magnet 94. When the switching means 128 is in the upper-case state, then certain of the fingers 127 have contact with certain fingers 129 so that the following conditions prevail: The lead 126^a is in circuit with the lead 142 for the magnet 92, the leads 126^c, 126^d and 126^e are in circuit with the lead 143 for the magnet 93, and the lead 126^f is in circuit with the lead 145 for the magnet 95. It is thus evident that at the operations of the various type keys 22 the appropriate stopping conditions are established for limiting the clockwise circumferential movement of the feed dog 32 in accord with the feed step that is required to ensue, and this is true whether typing is done in lower or upper case. The contacts 107, 108 are of lightly flexible material and offer thus very little resistance to the operations of the type actions, and over a small operating range, so that the imprint force of the type bars is practically unaffected. This is highly important, particularly also because the machine includes a usual settable mechanism, not shown, universal to the type actions, for varying the strength of imprints, and if the contacts 107, 108 were a strong impeding influence, such influence would have a disproportionate effect for different settings of such mechanism.

The contacts 107, 108 open early in the return of each operated type bar so that new stop pin selections can occur in quick succession. Obviously, the wiring may include spark-suppressing condensers, but such have not been shown. While magnets are preferably used the term should be interpreted to be embracive of solenoids.

The contacts 107 may be stamped from a single piece of sheet metal and mounted along with the individual contacts 108 within a housing comprising an inverted channel member 148 and a bottom cover 149, the latter secured by screws 150 to studs 151 in the member 148. The operating arms 111 for the contacts reach into the stated housing through vertical guide slots 152 provided in the member 148, the entire arrangement being such that the contacts 107 and 108 are well shielded against dust. The housing 148, 149 is generally co-extensive

with the spread of the key-levers 16 and is suitably attached at each end to the side walls 23 of the machine.

In Figure 8 there are shown three space bars 151, 152 and 153 respectively to cause the machine to space one, two and three increments. The space bar 151 is on a lever 154 and at the rear has an articulation with a transverse lever 155. The latter lever 155 has at its right end an upreaching wire link 156 which at the top has a reversing bend to include the aforescribed stop pin 61. To prevent the link 156 from turning it is nested in an open slot 159 provided in the plate 70. A spring 158 urges the lever 154 to its normal position seen in Figure 8. This locates the stop pin 61 above the swinging range of the escapement dog 32. At the operation of the space bar 151 the stop pin 61 moves downwardly into stopping range of said dog 32. The lever 161 has a hook 162 for drawing a space actuator 163 into operation-receiving relation with the constantly driven power roll 15. Thus, at operation of the space key 151 there ensues a forward movement of the actuator 163 which in turn, through a link 164, rocks a bail 165, the latter including an arm 166 whereby it acts on the dog operating lever 85. The shaft of the bail is pivotally supported at its left end in the left side wall 23 and, as seen in Figure 6, has pivotal support at its right end in a bracket 168 which in a manner not shown is carried fast on a crossbar 170 of the machine. When the space bar 151 is operated, the stop pin 61 is projected and the escapement dog 32 is momentarily operated clear of the escapement wheel 33 and moves from the abutment 47 to be re-engaged again by the stop pin 61 with the escapement wheel 33 one tooth beyond the last engagement and to measure out to the carriage a single increment step. Thereafter the parts are again in the position seen in Figure 2. The actuator 163 has a nose 167 which rides into engagement with the power roll 15 and whereby the actuator is disconnected. The arrangement is such that the operation of the actuator is very momentary, wherefore the dog operating lever 85 restores immediately after operation.

The space bar 152 is on a lever 169 which by a transverse lever 171 is in communication with the lever 161 for effecting connection of the actuator 163 with the power roll 15. Said lever 169 includes a branch 172 having a pin 173 to act upwardly on an arm 174 for closing a pair of contacts 175. Having reference to Figure 7, it will be seen that actuation of the key 152 establishes a closed circuit for the magnet 92, causing the projection of the stop pin 62. Since the key 152 also calls the space actuator 163 into operation, it follows that a two-increments space is resultant.

The space bar 153, being the one most frequently used, is extra long, and comprises a rockable unit consisting of two spaced arms 176. The left arm 176, through a lever 177, is adapted to operate the actuator engaging lever 161. The right arm 176 includes a branch 178 for upward operation on an arm 180. A pair of contacts 183 are closeable by said arm 180 to close the circuit for the magnet 93. Obviously, the key 153, when operated, produces a three-increments space of the carriage.

The keys 152 and 153 are pivotally supported on a common shaft 184 extending transversely of the machine. In connection with the said space keys it is to be observed that the stop pins 61, 62 and 63 become selected slightly in advance of the operation of the escapement operating arm 85. This is because the space actuator 163 includes a snatch pawl 185 which has capacity on the actuator 163 for some initial idle movement.

If the carriage is to execute steps of appropriate incremental value, then the escapement wheel 33 must at least momentarily come to rest before the escapement dog 32 is again released to move clockwise to take up a new tooth-hold in the escapement wheel. Ordinarily, the carriage 25 completes its letter-feed step, that is the dog 32 arrests the escapement wheel 33 in ample time, so that the static inertia of the carriage causes the escapement

wheel 33 to stand still while the escapement dog 32 moves clockwise and takes up its new tooth-hold in the wheel. However, this cannot be relied upon if one typing stroke succeeds so closely another that the carriage has not completed fully its first feed-step when the feed-dog 32 resultant to the second typing stroke moves again free of the escapement wheel. In such case the carriage and the escapement wheel 33 would continue movement as the dog 32 moves clockwise to take up its new tooth-hold. 5 Consequently the carriage would be temporarily out of control and there would result an excessive carriage movement. To guard against this, and yet not to impede unduly the carriage in its stepping movements, there is provided a secondary escapement dog 188 for co-action 15 with the escapement wheel 42 which is companion to and unitary with the escapement wheel 33. The escapement dog 188 is pivotally carried on the stud 86, above the lever 85, and is normally clear of the escapement wheel 42. At each typing operation the arm 81 which operates 20 the lever 85 to disengage the feed-dog 32 also operates an arm 190 which is integral with the dog 188, moving the latter between two teeth of the escapement wheel 42, see Figure 26. Specifically, a face 191 on the dog 188 moves to stand momentarily in the way of a tooth on the 25 wheel 42 as seen in Figure 26, assuring the halting of the wheel and the carriage long enough for the feed dog to take up its new position in the wheel, the angle at which the dog face 191 engages a wheel tooth being such that the tendency of the wheel to advance under the tension of 30 the carriage spring motor 28 has a camming influence favoring the restoration of the dog 188. If the dog 188 were associated with the escapement wheel 33 having the slightly undercut teeth, the carriage would be slow in getting under way in each feed step. The described 35 feature lends reliability of operation to the proportional spacing mechanism without detrimentally affecting its capability for high-speed of operation. A light restoring spring is associated with the dog arm 190.

Incidental to the operations of the space bars 151, 152 or 153 the lever 85 and the dog 188 are operated by the arm 166 and of course the escapement operation is 40 equally reliable and speedy.

It is one of the features of the invention to set the machine for widened spacing at the will of the operator. 45 In Figure 2 the supporting arm 45 for the escapement dog 32 has its branch 46 limitedly resting against the abutment 47 of the abutment arm 48. The said arm 48 and abutment comprise part of an abutment means which also includes a second abutment 193 afforded by a stud 50 194 which projects rigidly from the escapement bracket 38 downwardly. Means are provided whereby the abutment arm 48 is adapted to be given either the position seen in Figure 2 or the position seen in Figure 21. In the latter position of the said arm 48, the dog supporting 55 arm 45 has capacity for greater step-movement with the escapement wheel 33, namely it can move one escapement wheel tooth farther, at which time it limitedly engages the secondary abutment 193. The throat 87 in the pawl operating lever 85 is accommodating this greater step 60 movement as is illustrated in Figure 21, wherein the pin on the dog has entered a narrowed portion of the throat. Settable means, including a control knob 195, is provided to effect the movement of said abutment arm 48 from either one of the two positions seen in Figures 2 65 and 21 to the other position. Said settable means, however, at each new setting given thereto has effect on the arm 48 only resultant to the feed-dog moving from the engaged abutment 47 or 193. At the time it is desired to effect a change in the condition of the abutment means for future effectiveness of the abutment 47 or the abutment 193, the extension 46 of the arm 45 is of course engaged with the abutment 47 or the abutment 193, and so as not to alter the position of the carriage, the prevalent condition of the abutment means 47, 193 must 70 75 be maintained until in the next escapement operation.

the dog 32 moves from the abutment 47 or 193 that happens to be engaged.

From Figure 2 it will be noted that if the extension 46 of the dog supporting arm bears with pressure against the abutment 47, the arm 48 is thereby held against swinging movement to the position seen in Figure 21. To further insure against such swinging movement of the arm 48, a tooth 196 on the latter, see Figure 2, is adapted to lie in a notch of the said extension 46. If the abutment arm 48 has the position seen in Figure 21, the stated extension 46 lying against the stationary abutment 193 blocks said arm against movement to the Figure 2 position.

A mechanism is adapted to be given one condition to place said abutment arm 48 under an urge to move from said Figure 2 position to the Figure 21 position, said urge, however, having effect only incidental to the first escapement operation following such conditioning, that is when the stated extension 46 moves from the abutment 47. The same mechanism is adapted to be given another condition to place said abutment arm 48 under an urge to move from said Figure 21 position to the Figure 2 position, such urge having effect only incidental to the first escapement operation following thereafter, that is when the extension 46 moves away from the abutment 193. The said mechanism comprises a torsion spring 200 carried on the stud 50 and having two legs straddling a pin 201 projecting downwardly from the abutment arm 48. The two legs of said spring 200 straddle also the upper-end portion of an arm 202 which is pivotally carried at 204 on a bracket 203 fastened upon the crossbar 170, see Figures 5 and 6. In Figure 5 which is a right-hand side view, the arm 202 is shown in the forwardly swung position contacting with the front leg of the spring 200 so that the rear leg bears with tension forwardly on the pin 201 of the abutment arm 48. The said arm 202, see Figure 6, is adapted to be held in the Figure 5 position under the control of the knob 195 which is provided on the right end of a shaft 205, such shaft at its left end being bent to form a crank pin 206 and the latter extending into a slot 207 of the arm 202. Near its left end the said shaft 205 is pivotally supported in the bracket 203 and at the other end it has pivotal support in the right end side wall 23 of the machine.

The shaft 205 extends through a clearance hole in an outer shell 208 of the machine. By turning the shaft 205 counter-clockwise of Figure 5, by the knob 195, the said arm 202 is moved to the indicated dot-and-dash position. In such movement of the arm 202 the rear leg of the spring 200 is moved to the position seen in Figure 20 and consequently the abutment arm 48 is under a rearward urge of the front leg of said spring. At the time the said arm 202 is so moved rearwardly the abutment arm 48 is detained as shown in Figure 20 by the extension 46 of the dog supporting arm 45. The front leg of the spring 200 therefore is prevented from moving the butment arm 48 rearwardly until a typing or spacing operation causes the clockwise movement of the dog supporting arm 45. When this happens, the abutment arm 48 snaps rearwardly to the position seen in Figure 21.

When the said arm 202 is moved from the position of Figure 21 to the forward position of Figure 5, the rear leg of the spring 200 will conversely bear forwardly on the abutment arm 48, but will be able to position it in its forward, limiting position only after the extension 46 of the dog supporting arm 45 in the next escapement operation moves clockwise beyond the abutment arm 48.

The machine includes a provision for detaining the dog supporting arm 45 upon its movement against either of the abutments 47 and 193. Such provision is very important for placing the carriage under uniform conditions under control of the escapement at the termination of tabulations, carriage returns and back spacing operations. It facilitates also manual positioning of the carriage under uniform conditions, accurately and with greatest ease,

as will be evident hereinafter. The said holding provision is effective at the conclusion of each escapement operation until the next escapement operation is instituted. The stated holding provision, see Figure 2, comprises a pawl lever 210 having two ratchet teeth and being pivotally supported on a stud 211 projecting downwardly from the escapement bracket 38. An arm 212 integral with the dog supporting arm 45 cooperates with the teeth of said pawl lever 210 so that normally the pawl supporting arm 45 is held against clockwise movement from either of said abutments 47 or 193. The said pawl lever 210, under the constant urge of a spring 213, tends to move to effective position.

At every operation of the dog releasing lever 85 effected by the arms 81 or 166, the secondary escapement dog 183 is swung momentarily into controlling engagement with the escapement wheel 42. Said secondary dog 188 has a pin 214 whereagainst the pawl lever 210 is adapted to lie under the tension of the spring 213. Operation of the secondary dog 188, as illustrated in Figure 26, releases the pawl lever 210 from the arm 212, so that the escapement dog 32 which has been disengaged concomitantly, will move clockwise to take up its new toothhold. The operation of the pawl lever 210 is very momentary and as the escapement dog in its new toothhold moves counterclockwise to the limit of either the abutment 47 or the abutment 193, the arm 212 is again caught by one or the other of the ratchet teeth of the pawl lever 210. Thus the pivot 44 of the escapement dog 32 is normally substantially stationary.

To facilitate ready positioning of the carriage 25 manually at will and in different incremental positions, leftwardly or rightwardly, the carriage includes thereon, see Figure 1, a bail structure comprising a bail bar 215 co-extensive and parallel with the carriage. The bail structure further comprises at each opposite end of the carriage an arm 216, such arms having a rock shaft 217 extending therebetween and having pivotal support in the carriage ends. Each of the arms 216 includes an operating finger piece, not shown, and the bail structure, under the urge of a spring 218, has normally the position seen in Figure 1. Substantially in the middle of the machine there is arranged an arm 220 for operation by the bail bar 215 regardless of the position the carriage may occupy. Said arm 220 is fast on a short shaft 219 which has pivotal support in a housing that supports portions of a tabulating mechanism. On said shaft 219, a distance leftwardly of the arm 220, there is a downreaching arm 221, a lower portion of which is shown in Figures 2 and 6. Whenever the carriage supported bail 215 is operated it results in a pivotal displacement of the arms 220 and 221. This through action of the arm 221 on the lever 85 will release the escapement dog 32, but not the supplementary dog 188. Therefore the escapement dog 32, although released, is prevented under control of the pawl 210 from moving circumferentially. With bail 215 maintained actuated, the carriage can then be freely located as required, the escapement dog 32 taking immediate and accurate incremental control over the carriage as the bail 215 is permitted to restore. In other words, the carriage settles with less than one increment advance movement when the escapement dog 32 is restored, and this is true whether the machine is set for normal or widened spacing. Of course, also when the carriage is relocated by a push in return direction, the carriage settles also with less than a single increment advance.

A number of special problems arise in connection with providing an efficient, accurately functioning tabulating mechanism in machines embodying proportional letter-spacing mechanism. One difficulty arises in view of the rebound of the carriage incidental to its tabulating arrest coupled with the requirement to bring the carriage accurately to rest in a definite incremental feed position.

The machine, see Figures 1, 2, 22 and 23, embodies a

member or wheel 225, which is fast on the escapement wheel shaft 34 and has teeth at intervals corresponding to three teeth of the escapement wheel 33. A stop slide 226 stands normally clear of the coarsely-toothed wheel 225. When the carriage is tabulated and approaches a position whereat the tabulating run is to be terminated, the said slide 226 is automatically caused to move into engagement with said wheel 225 to intercept it by action with one of its teeth.

The carriage may embody a bar 27, see Figure 12, extending lengthwise thereon and having key-settable, tabulation-terminating elements 228 or stops arranged in a row therealong, the arrangement being substantially as disclosed in the patent to Helmond, No. 2,278,010, dated March 31, 1942. One of said elements 228, including fragments of the stated bar 227, is indicated also in Figure 1. The spacing of said elements 228 agrees with the spacing of the coarse teeth on the wheel 225, namely said elements are spaced at triple-feed increments. The control elements 228 are individually settable in the manner generally disclosed in said Patent No. 2,278,010, downwardly on the bar 227 to tabulation controlling positions, two of the elements 228 being shown set in Figure 12. In a manner hereinafter to be explained, any of the elements 228 may be brought into registration with a narrow setter 230 to be set by downward actuation of the latter, the machine having in the keyboard of the machine a set key, not shown, and said setter 230 being responsive to said set key. Directly below the setter 230, is a restorer 231 of conventional construction, and including a cam face 232. The said restorer is operable upwardly under key control, not shown, to restore any set element 228 situated directly thereabove. Moreover, when said restorer is operated, the cam face 232 will restore any element which by rightward carriage movement is riding upwardly thereon.

Within the tabulator housing 234 there is an element 235 projectable from an idle lower position seen in Figure 12, upwardly to stand in cooperative range with said control elements 228. Said projectable element 235 is in the form of a generally vertical reed which near its lower end is guided in a slot of a plate 236 which is fast in the housing 234. Said projectable element 235 has near the upper end a slot 237, see Figure 1, through which there extends a guide stud 238, the latter having support in the opposite side walls of the housing 234. An ear 240, integral with the reed or element 235, affords a saddle 241 for a pin 242 on an arm 243. The right end of the arm 243 has an open slot whereby it is pivotally seated on a stud 244, there being a spring 245 connected to said arm to keep it normally rightwardly urged to the limit of the stated slot, as well as downwardly about the pivot stud 244. Said stud is fast on a projection downreaching from the top plate 246 of the housing 234. The pin 242 bears down in the saddle 241 so that said projectable element 235 has normally the position seen in Figure 12, wherein a stop lug 247 thereon rests on the plate 236. Said pin 242, by bearing down under the influence of the spring 245, will settle to the lowest point in the saddle 241 and thereby will give normally the upper end of said element 235 the lateral position seen in Figure 12.

At operation of a tabulator key 248, see Figure 1, a link 250 is power raised by a mechanism later herein to be described. Said link, near its lower end, has guidance in a slot of the plate 236 and at its upper end has an open slot 251 straddling a reduced portion of the stud 238. A stop lug 252 of said link rests normally upon the plate 236. The top end of said reed underlies a shoulder 253 of the arm 243 with slight clearance. A spring 254 inferior to the spring 245 extends with tension between the element 235 and the reed 250. When the link 250 is operated, it displaces the arm 243 upwardly, as is evident from Figures 13 or 14, and the element 235 will readily follow under the urge of the spring 254, as

directed by the pin 242 resting deep in the saddle, provided, however, that no tabulation controlling element 228 happens to stand in its path.

Due to the fact that the position of the carriage is variant in accord with the stated small feed increments, a tabulating control element 228 may make it infeasible for the element 235 to move straight upwardly, that is the element 235 may clash with a set element 228. In such event, the light spring 254 allows the element 235 to be temporarily held up. While the operation of said arm 235 progresses, the pin 242 on the arm rises from the bottom portion of the saddle 241 so that the element 235 can glide into position either leftwardly, as in Figure 13, or rightwardly as in Figure 14. The top of the projectable element 235 has a sharp edge and also the lower ends of the settable elements 228 are sharp-edged. This gives the projectable element 235 a better opportunity to glide upwardly into position. In the stated operation the said element 235 is urged upwardly by the light spring 254 and is unable to restore any set element 228 with which it may clash, it being understood that usual detent springs hold said elements either in idle or set positions.

The upward actuation of the link 250 is effected in response to the tabulator key 248 by a mechanism which is fully disclosed in the patent to Helmond No. 2,303,878, dated December 1, 1942. Said key 248, by downward action on a transverse lever indicated at 255, depresses a lever 256 which by a hook 257 will lower an actuator 258 into motion-receiving relation with the constantly turning power roll 15, see Figure 9. Said actuator 258 consequently receives a power stroke, imparting thereby, by means of a link 260, a swinging motion to a rocking assembly 261 comprising an arm 263 and a shaft 262, said swinging motion, considered in reference to Figures 1 and 9, being counter-clockwise. The shaft 262 extends transversely of the machine as shown in Figure 6, and has pivotal support in the bracket 168 and in the right side wall 23. At the middle of the machine the shaft 262 has an arm 265 which through a link 266 is connected to a lever 267, the latter having connected thereto the lower end of the link 250. Near the left end the said shaft 262 has fast thereon an upreaching arm 268 for action on the dog operating lever 85.

By the described mechanism there results in response to an operation of the tabulator key 248 an upward displacement of the link 250 to cause the resilient projection of the element 235. Concomitantly also a release of the escapement dog 32 is effected to free the carriage for tabulating travel.

The stated actuator 258 is divorced automatically as said rocking structure 261 reaches operated position, it having a tail 270 riding into the power roll 15 whereby the power roll will then force it out of engagement for immediate return to restored position by a spring 259, independently of the rocking assembly 261, the actuator having a slot 271 permitting this. On the other hand the rocking assembly 261 inclusive of the arms 266 and 268, is automatically detained in operated position through a latch 272 which automatically snaps into position behind the arm 268. The said latch 272 has pivotal support on a stud 273 projecting laterally from a vertical ear of the escapement bracket 38. A spring 274, see Figure 2, has a constant bias to move the latch to effective position downwardly behind the arm 268. However, normally the said latch 272 lies with tension upon the top end of the arm 268.

The stop slide 226, see Figure 1, 22, and 23, has an articulation at its rear end with an upright lever 277 which is pivotally carried on a rock shaft 278. A part of the lever 277 which extends above the rock shaft 278 has associated therewith a latch 280 which, under the urge of a spring 281, see Figure 2, is normally in position to hold said lever against movement clockwise of Figure 1 by a strong spring 282. The lever 277, so held, causes

the stop slide 226 to stand normally clear of the coarsely toothed wheel 225. From Figures 1 and 18 it can be seen that the end of the stop slide 226 adjacent to the wheel 225 is situated in a rectangular hole afforded by a block 283 having a wide notch 284 at its bottom side and being fastened upon the escapement bracket 38. A spring 285 urges the stop slide 226 against the left side of the notch 284.

The stated latch 280 has pivotal support at 286 on the underside of the housing top plate 246, and includes a face 287 standing normally slightly to the left of the projectable element 235, see Figures 2 and 12.

The tabulating movement of the carriage which ensues resultant to the operation of the tabulator key 248 is terminated automatically in response to any control element 228 riding in its tabulating advance against the projected element 235 and displacing it slightly about its lower end. Said element 235, in being so displaced, acts on the face 287 to swing the latch 280 free of the lever 277. Said lever 277 under the tension of the spring 282 moves immediately to snap the stop slide 226 into engagement with the coarsely toothed wheel 225. The face 287 of the latch arm 280 is so correlated with the projectable element 235 that the release of the latch 280 occurs always just after one of the leading edges of the teeth on a wheel 225 passes the stop edge of the slide 226. In other words the stop slide 226 snaps into position approximately when the wheel teeth have a relation thereto as seen in Figure 18. Because of this the stop slide 226 has ample time to move reliably into position to intercept the next tooth of the wheel 225. In effecting the arrest of the wheel 225 the stop slide reacts against the left side of the notch 284 and there ensues momentarily a rebounding movement of the carriage and the wheel 42 in which the stop slide 226 may be carried along by the wheel 225 until it contacts against the right side of the notch 284. If the rebound is in excess of the said notch 284 then the back side of the wheel tooth against which the slide 226 lies glides therewith a little further but insufficiently for said stop slide to lose control over the wheel 225, the latter settling after a short time interval, accurately defined by the slide 226 resting against the left side of the notch 284.

The projected element 235, after effecting the release of the latch 280, is moved a little farther by the element 228 and, before the stop slide 226 intercepts the wheel 225, the right edge of the saddle 241 carries the arm 243 slightly rightwardly for the shoulder 253 of the arm 243 to ride off the top end of the link 250. This causes the immediate restoration of the projectable element 235 to normal position by the arm 243 which is under the strong downward bias of the spring 245.

It will be noted that neither the projectable element 235 nor the control element 228 riding thereagainst takes the blow of the tabulating carriage and consequently these parts, as well as also the bar 227, can be of very light construction. Obviously the wheel 225 can be of ample strength and if desired the block 283 may be cushioned to reduce noise.

The upper end of the link 250 is adjustable with respect to the shoulder 253, parallel to the carriage, by screwing the guide stud 238 in the housing 234 to different positions, it being noted that said guide stud has a shoulder against which the link 250 bears under the influence of the spring 254. This allows the restoration of the projectable element 235 to be timed to occur after the release of the latch 280 and before the arrest of the carriage.

The shaft 278 which pivotally supports the lever 277, has pivotal support at one end in the right side wall 23 of the machine and at the other end in a plate 288 secured to the left side of the housing 246, see Figure 2. At its left end said shaft 278 has fast thereon an arm 290 which with some clearance normally overlies a finger of the latch 272, see Figure 1. Said shaft 278 has also

fast thereon a downreaching arm 291 having two pins 292 straddling the lower arm of the lever 277, a spring 293 attached to the arm 291 causing it to have normally the position seen in Figure 1 wherein the rear pin 292 lies forwardly against the lever 277. The shaft 278 has a further arm 294 near its right end whereon there is turnably supported on a stud 295, a cam roll 296. The said cam roll is associated with a tire 297 of rubber or other resilient material provided on a wheel 298 which continually turns with a pulley 300 of a belt drive for the power roll 15, the direction of rotation being indicated in Figure 1 by an arrow. The cam roll 296 has a hub 301 provided with opposite flats 302. A spring 303 has two legs tensioned toward each other in said flats to detent normally the cam roll 296 to have the position seen in Figure 1. The said spring 303 includes a few turns surrounding a supporting pin 304 and tensioning said legs toward each other. The cam roll 296 stands normally lifted off the tire 297 in the position seen in Figure 1.

Whenever at the conclusion of the tabulating movement of the carriage the lever 277 is spring actuated in response to the operation of the latch 280, the arm 291 will follow under the tension of the spring 293, whereby the arm 294 brings the cam roll 296 into pressure contact with the tire 297. The said cam roll 296 has preferably a serrated periphery. Upon contact with the tire cam roll 296 will be driven thereby to execute a single turn. During a first quarter of this turn a concentric portion of the cam rides on the tire 297, and nothing significant happens. During a second quarter turn an eccentric portion of the said cam causes the arm 294 to swing counter-clockwise of Figure 22 and the arm 290 actuates the latch 272. This operation is shown in progress in Figure 22, wherein the latch 272 is on the point of release for freeing the arm 268 of the rocking assembly 261. Therefore, the dog controlling lever 85 will restore the escapement dog 32 at the next moment to gain control over the carriage. During the rotation of the cam 296 to the Figure 22 position, the carriage has ample time to rebound and come fully and accurately to rest against the stop slide 226. Continuing to turn the cam will displace the arm 294 counter-clockwise beyond the Figure 22 position, and when the crest of the cam 296 rides on the tire the arm 291 by its front pin 292 will have restored the lever 277 slightly beyond the normal position, the latch 280 springing to effective position for holding the lever 277. The stop slide 226 consequently will have moved clear of the coarsely toothed wheel 225 and will be held thereat. As soon as said stop 226 has so moved clear, the carriage will move slightly taking up free play between the escapement dog 32 and the escapement wheel 33. It is to be remembered here that during the tabulation the one or the other tooth on the pawl 210 holds the supporting arm 45 of the escapement dog 32, wherefore at the end of each tabulation the escapement dog 32 takes uniformly charge over the carriage with almost no additional movement thereof. The control which the cam 296 exercises is such that ample time is allowed for the carriage to settle accurately against the stop 226 before the escapement dog is allowed to reassert its control, this being extremely important because the dog 32 must engage the appropriate fine tooth of the escapement wheel 42.

After the tire 297 turns the cam 296 past its crest, the turn of the cam is concluded by the tension of the legs of the spring 303 against the opposite flats 302. Moreover, the said spring legs will then detent or hold the cam on the arm 294 in the normal position, see Figure 1. As the cam turns toward the stated normal position on the arm 294, the spring 293 swings the shaft assembly 290, 291 and 294 to the position seen in Figure 1, wherein the rear pin 292 of the arm 291 rests limitedly against the rear of the lever 277. This leaves the mechanism in normal state, ready to serve at the end of the next tabu-

lation, or the end of a carriage return, as will become evident hereinafter.

A serious problem arises in proportional spacing typewriters also in connection with carriage returning operations. This is in view of the fact that the escapement must take accurate control over the carriage at the appropriate incremental feed position. To overcome the difficulty, the carriage is brought to rest at power returns in agreement with a certain multiple of the small carriage feed increment, whereby reliable and accurate return control is effected. The mechanism provided for this has partially been described in connection with tabulating mechanism and includes the coarsely toothed wheel 225 and the stop slide 226 which is normally clear of said wheel.

Referring to Figure 11, the actual carriage return mechanism may be substantially that of the patent to Sagner, No. 2,541,295, dated February 13, 1951. The numeral 307 indicates a speed reduction drive casing. The input shaft 310 of the speed reduction drive is driven by an electric motor 308. Said drive has a driven low-speed shaft 311 carrying outside of said casing 307 the pulley 300 and the wheel 298. The motor 308 runs continuously while the machine is in use, and so said shaft 311, concentrically arranged with the shaft 311, within the casing 307, is a drum 312 which normally is disconnected from the shaft 311. From said drum extends a carriage return draw band 313, over two idler pulleys 314, to the left end of the carriage 25. A clock spring associated with said drum 312, but not shown, causes the latter to take up slack in the draw band 313. The drum is connectable for rotation by the shaft 311 by movement of a clutch controlling arm 315 from the full-line position to the dotted position, see Figure 11. A lever 316 is connected by a link 317 to the arm 315, the said lever being fast on a short rock shaft 318 having pivotal support in the rear wall of the tabulator housing 234 and a bracket 320 within the housing. The arm 315 is under the constant urge of a spring 321 to move to its closed clutch position, but a latch 322 normally overlies the lever 316 and thereby causes said arm 315 to be held against clutch closure. The said latch 322 has pivotal support on the side wall 23 and is releasable by the operation of a carriage return key 324 which surmounts a stem 325. A lever 326, pivoted at 327, is at its front end pivotally connected with the stem 325 and has a pin 328 underlying a forwardly reaching branch of said latch 322. The lower end of the key stem 325 is pivotally jointed on an arm 330 of a bail comprising shaft 331 extending transversely of the machine and pivoted in the machine side walls 23. The key 324 and connected parts, under the tension of a spring 332, have normally the positions seen in Figure 11. When key 324 is operated the latch 322 swings rearwardly off the lever 316, to allow its upward movement, wherefore the spring 321 will move the arm 315 to closed-clutch position. The drum 312 now clutched to the shaft 311 will wind the draw band 313 thereon to return the carriage. The carriage includes a usual return-terminating margin stop 333 which is adjustably positionable along a rack bar 334 in positions variant in accord with the incremental spacing of the teeth of the coarsely toothed wheel 225. When lever 316 moves upwardly at the release of the latch 322, a slide 335 connected to an arm of the lever, by a pin 337, moves a carriage return counter stop 336 leftwardly in an opening 338 of the housing top plate 246. The carriage return counter stop 336 comprises an upstanding element which at its bottom has pivotal support at 340, and which is under a constant upward and rightward bias of a spring 341. As the return terminating stop 333 is an instituted power return moves rightwardly, it will meet and effect the rightward displacement of the counter stop 336 somewhat beyond the position shown in Figure 11, against the right side of the opening 338, and through the slide 335 will swing the lever 75

316 clockwise beyond the normal position seen in Figure 11. This results in a clutch opening movement of the arm 315. If the carriage return key 324 has meanwhile been released, the latch 322 will reassert its control over said lever 316. In the event the carriage return key is still held operated at the termination of the return, then an auxiliary latch 342 will temporarily detain said lever 316, the latch 322 taking over control when the key 324 is released. The power return of the carriage is thus terminated automatically.

The escapement dog 32 is moved out of the escapement wheel 33 incidental to each depression of the carriage return key 324. To this end the bail shaft 331 controlled by the carriage return key 324 has leftwardly of the 15 middle of the machine an arm 343 from which extends rearwardly a push link 344. A rear portion of said push link 344 overlies a lug 345 of a lever 346 which is pivotally carried on the shaft 262 and has its upper end posed behind a dog releasing lever 85. The said push link 344 has a shoulder 347 for operation on said lever 346. As said lever 346 effects the operation of the dog releasing lever 85, a latch 348 shown in Figures 1, 2 and 6 swings under the tension of a spring 349 down in back thereof to hold it operated for the duration of the carriage return. The latch 348 is similar to the latch 272 and supported alongside thereof by the same stud 273.

At the time the lever 316 springs to closed-clutch position, an arm 350 on the supporting shaft 318 therefor moves from the Figure 2 position to the Figure 23 position. A hook element 351 pivotally connected with the latch 280 has normally the position seen in Figure 2, resting idly rearwardly against the arm 350. As the arm moves to the position of Figure 23, said hook 351 under the tension of the spring 281 swings rearwardly, rendering the said arm 350 operatively connected with the latch 280 for effecting its release. The said hook element 351 has pivotal connection with said latch at 352 and the spring 281 has the dual purpose of biasing the hook element rearwardly and the latch 280 toward effective position. When at the end of the carriage return the return terminating margin stop 333 displaces the counter stop 336 rightwardly and renders the carriage return drive inactive, the lever 316 operates the arm 350 rightwardly and through said hook effects automatically the release 45 of the latch 280. Resultingly the stop slide 226 snaps into the coarsely toothed wheel 225, the same as at the end of tabulations, the wheel 225 turning at the time still in reverse direction. The mechanism is timed to release the latch 280 when the carriage reaches the position 50 whereat it ultimately is required to come to rest. However, the opening in the top plate 246 permits the carriage to overrun by momentum about two or three increments, whereafter the carriage will settle in carriage feed direction under control of a tooth on the wheel 225 abutting the stop slide 226.

Incidental to the stop slide 226 moving into position in the wheel 225, the arm 291 will swing clockwise of Figure 1 under the tension of the spring 293 so that the cam roll 296 engages the tire 297 and will receive a turn therefrom the same as at the end of a tabulation. When in the first part of such turn the cam reaches the position of Figure 22, the arm 290 will release the latch 348, causing the escapement dog 32 again to take charge over the escapement wheel 33. This is after sufficient time has elapsed for the carriage to settle, that is for a coarse tooth of the wheel 225 to come to rest against the stop slide 226. As the crest of the cam 296 rides onto the tire, the stop slide 226 becomes restored by the front pin 292 of the arm 291. Concomitantly, an arm 354 fast on the shaft 278 pushes the hook 351 forwardly, free of the arm 350, wherefore the latch 280 moves into position to hold again the lever 277 in its restored position. After the slide 226 moves out of the wheel 225, the carriage 70 advances slightly until the escapement wheel 33 catches up

solidly against the dog 32. The carriage is then in an accurately returned position.

It is possible that at the time the carriage return run is terminated the operator still holds the carriage return key 324 depressed. So that in such event the lever 346 is free to return at the release of the latch 348, the latter has a rod 355 linked thereto which by a collar 356 is adapted to lift the push link 344 at each release of said latch 348. At its lower end said rod 355 has guidance in a hole provided in the crossbar 170.

The carriage may be effectively and accurately returned if it is only one or two increments advanced from returned position. It will be remembered that the operation of the carriage return key 324 effects the release of the escapement dog 32 through a train of parts 344, 346 and 85. In consequence of this the carriage is adapted to advance momentarily before the carriage return draw band 313 has a carriage returning effect. The stated momentary advance of the carriage moves the return limiting stop 333 leftwardly from the counter stop 336 sufficiently to lend the lever 316 capacity for a full clutch closing movement. The sequence of operation so provided renders the carriage return mechanism reliably operative at all times and the stated sequence is favored also by the draw band 313 picking up the carriage with a delay by first operating a usual line spacing device on the carriage, see the aforementioned patent to Sagner.

An operator may institute a tabulation without there being a tabulation terminating element 228 in a position to engage the element 235 for terminating the tabulation. Under such condition the tabulating run of the carriage is terminated by a line end margin stop 357 riding against and displacing the counter stop 336 leftwardly in the opening 338. The said counter stop 336 has projecting rearwardly therefrom a pin 358 which, as such counter stop is moved leftwardly, displaces the projectable element 235 leftwardly of Figure 12. This releases the latch 280 so that the stop slide 226 will engage the coarsely toothed wheel 225 as in the case of a regularly terminated tabulation. Furthermore, as in a regularly terminated tabulation the cam roll 296 engages the tire 297 and will receive therefrom a cyclic turn. In such cyclic turn, after a first time interval, the release of the latch 272 is effected which causes the engagement of escapement dog 32. After a further time interval the stop slide 226 is restored and all parts assume their normal positions.

It has been stated that responsive to the operation of the carriage return key 324 the carriage return counter stop 336 is moved leftwardly by the lever 316. Obviously, at such time the projectable element 235, even though it is operated leftwardly by the pin 358, must not release the latch 280. To this end the projectable element 235 has a cut-out as at 360 so that it stands in operative range of said latch 280 only when it has been projected for tabulation terminating control.

As stated hereinbefore, the tabulation control elements 228 are provided at intervals corresponding to three feed-increments. This in terms of escapement wheel movement is in accord with the spacing of the teeth on the coarsely toothed wheel 225. Obviously, when it is desired to set an element 228, the carriage may occupy an incremental position wherein none of said elements is in registration with the setter 230. Any control element 228 which is required to be set, therefore, must be brought into registration with the setter 230 before said setter is operated, preferably under control of a key in the keyboard. The control elements 228 are concealed under a cover, not shown, and there arises the problem of how to bring the carriage conveniently and with certainty to the proper incremental position for the setting of a control element 228. It is evident that if the carriage is first moved to bring any element 228 into registration with said setter 230, then the particular element 228 which is required to be set can thereafter be brought accurately and conveniently into registration by simply spacing the car-

riage in triple feed-increments, forwardly or backwardly.

The machine accordingly includes a device which is operable to effect automatically an incremental relocation of the carriage to bring a tabulation control element 228 into registration with said setter 230. Said device comprises a pawl 361 for back-spacing the wheel 225, located in the plane of the coarsely toothed wheel 225, see Figure 15, and having normally the position shown in this figure, free of the wheel 225. The pawl 361 is linked as at 362 to an arm 363 which is part of a rockable bail comprising a fulcrum shaft 369 and also an arm 364 having a roll 365 contacting a cam 366. The latter is turnably provided on a reduced shaft end 367 of the power roll 15. Adjacent to said cam 366, fast on the shaft end 367, is a toothed wheel 368. A spring 370 urges the arm 364 toward the cam 366 and normally the roll 365 bears on a low spot of the cam as in the Figure 19a. The said cam 366 carries a pawl 371 which under the urge of a spring 372 tends to couple the cam 366 for rotation with the toothed wheel 368. However, a leg 373 of the pawl 371, intercepted by a dog 374, holds the pawl 371 normally divorced from the wheel 368 as in Figure 19a. A key lever 375 has an articulation with the dog 374 to operate it and thereby to free the pawl 371 to engage the toothed wheel 368. If the key lever 375 is operated momentarily, then the cam 366 will execute a single turn, causing a reciprocation of the pawl 361. Any number of reciprocations of said pawl 361 can be obtained by holding the lever 375 operated for different time lengths.

The back space pawl 361 is guided near its front end by a stud 376 which reaches upwardly from the escapement bracket 38 into an opening 377. A spring 378 urges the pawl toward the wheel 225 but an edge 380 provided by said openings, by cooperation with the stud 376, causes the pawl to lie normally clear of the wheel 225, as in Figures 15, 17 and 19.

In Figure 15 the wheel 225 is in such an incremental position that one of the tabulation-terminating elements 228 on the carriage is in registration with the setter 230. However, the wheel 225 may normally be in the position seen in Figure 19, namely, one feed increment further advanced. Or it may be in the position seen in Figure 17, namely, two feed increments further advanced. It will now be seen that if an operation of the back space pawl 361 is effected with the wheel initially standing in any of the stated incremental positions, the wheel will be back spaced so that it will reach the same coarse tooth position, namely, slightly beyond the position seen in Figure 16. A face 383 afforded in the opening 377 of said pawl, at the conclusion of the back spacing operation, moves solidly against the stud 376 so that the pawl 361 cannot move leftwardly. Moreover, the front end of the opening contacts solidly the stud, the sum effect being that the wheel becomes blocked against overthrow.

The so limited actuation of the wheel 225 is excessive by a small fraction of one feeding increment, allowing the feed pawl 32 to snap freely into position on the escapement wheel 33, the carriage settling solidly against the dog 32 as the back space pawl returns.

In Figure 17 there is indicated a path which the pawl edge will take to back space the wheel 225 the required fractional tooth space, namely, a double feed increment. Similarly in Figure 19 the path of the pawl edge toward the wheel is indicated, the wheel being back spaced one single feed increment.

After the wheel 225 has been back spaced once, as stated, the carriage can be brought to the appropriate position for setting a tabulation-terminating element 228, by appropriate control of the back space key lever 375 to obtain an appropriate number of operations of the back space pawl 361 or by operation of the three-increments space bar 153.

The machine preferably includes the mechanism of the patent to Sagner, No. 2,633,964, dated April 7, 1953, whereby the aforementioned margin stops 333 and

357 are conveniently settable from the keyboard of the machine. In this connection it is to be noted that the stated margin stops are adjustable along the supporting rack 334 to different positions in accord with triple feed increments and that in the process of adjustment of either of said margin stops, the back space key 375 and the space key 153 are selectively used to bring about the required stop relocation.

For back spacing the carriage in single feed increments, there is associated with the escapement wheel 33, see Figure 4, a back spacing pawl 384. This pawl is supported on a lever 385 which normally has the position seen in Figure 4. A spring 386 tends to engage the pawl with the wheel but a pin 387 keeps the pawl normally free thereof. The lever 385, in a manner not shown, is operable rearwardly under control of a single increment back space key 388 shown in Figure 8. The operation of the pawl 384 is limited by a pin 389 so that throw of the wheel 33 is restricted to a little more than one tooth or feed increment.

The mechanism and features of the invention have been exemplified in connection with an escapement rack 33, etc. of rotary form, but, obviously, certain features of the invention are equally useful in connection with toothed members of straight form. Also the proportional feed mechanism may control a type supporting carriage for movement in respect to a paper support.

In general the invention is not restricted to the particular construction or method of operation set forth, but is intended to cover such modifications or departures as may be within the purposes of the improvements or the scope of the claims which follow.

What is claimed is:

1. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop movable into tabulation-terminating engagement with the teeth of said member but normally clear thereof, said toothed member and said stop being one on the frame and the other movable by the carriage, an element movable with the carriage, an element on the frame, one of said elements projectable into range with the other for engagement therewith in the tabulating advance of the carriage, means to project the projectable one of said elements and to free said carriage from the control of the letter-feed mechanism for tabulating advance, means responsive to the tabulating advance of one of said elements against the other to cause the engagement of said stop in the row of teeth of said member, and means responsive to the tabulating advance of one of said elements against the other to restore with a definite time delay the carriage to the control of the letter-feed mechanism and to retract said stop with at least an equal time delay.

2. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop movable into tabulation-terminating engagement with the teeth of said member but normally clear thereof, said toothed member and said stop being one on the frame and the other movable by the carriage, an element on the frame, one of said elements projectable into range with the other for engagement therewith in the tabulating advance of the carriage, means to project the projectable one of said elements and to free said carriage from the control of the letter-feed mechanism for tabulating advance, means responsive to the tabulating advance of one of said elements against the other to cause the engagement of said stop in the row of teeth of said member, a power device adapted to

be called into operation to execute a cyclic motion and resultant to a first part of such cyclic motion effecting the restoration of the control of the letter-feed mechanism over the carriage and resultant to a further cyclic motion 5 retracting said stop, and means responsive to the tabulating advance of one of said elements against the other to call said power device into operation.

3. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop movable into tabulation-terminating engagement with the teeth of said 10 member but normally clear thereof, said toothed member and said stop being one on the frame and the other movable by the carriage, an element movable with the carriage, an element on the frame, one of said elements projectable into range with the other for engagement therewith in the tabulating advance of the carriage, means to project the projectable one of said elements and to free said carriage from the control of the letter-feed mechanism for tabulating advance, means responsive to the tabulating advance of one of said elements against 15 the other to cause the engagement of said stop in the row of teeth of said member, a normally idle power device responsive automatically to the engagement of one of said elements against the other to execute a cyclic motion, and means operated by said power device to restore after a part cyclic motion the control of the letter-feed mechanism over the carriage and to retract said stop.

4. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop normally clear of said member and operable into engagement with the teeth thereof for tabulation-terminating action, said toothed member and said stop being one on the frame and the other movable by the carriage, a part whereagainst said stop is adapted to react for tabulation-terminating action, means giving the operated stop capacity to rebound relatively from said part and thereby enabling it to maintain its effected engagement in the teeth of said member during rebounding, an element movable with the carriage, an element on the frame, one of said elements projectable into range with the other for engagement therewith in the tabulating advance of the carriage, means to project the projectable one of said elements and to free said carriage from the control of the letter-feed mechanism for tabulating advance, and means responsive to the tabulating advance of one of said elements against the other to cause the engagement of said stop in the row of teeth of said member.

5. In a proportional spacing typewriting machine having type keys, and a carriage impelled to advance for letter-feeding and tabulating, the combination with a 60 letter-feed mechanism normally in control of the carriage and operable differentially under the control of the type keys to feed the carriage proportionally to the width of each character typed in terms of different multiples of a given feed increment, of a tabulating means for the carriage, comprising a member having teeth coarsely spaced corresponding to a given multiple of said feed increment, a stop under urge to move into tabulation-terminating tooth-hold with said member but normally clear thereof, said toothed member and said stop being one on the frame and the other movable by the carriage, latch means to hold said stop normally clear of said teeth, an element movable with the carriage, an element on the frame, one of said elements projectable into range of the other for engagement thereby in the tabulating advance 65 of the carriage, means to project the projectable one of

said elements and to free said carriage from the control of the letter-feed mechanism for tabulating advance, and means responsive to the tabulating advance of one of said elements against the other to release said latch means, wherefore the tabulating advance of the carriage will be terminated by said stop in cooperation with the coarsely spaced teeth of said member.

6. In a proportional spacing typewriting machine having type keys, and a carriage impelled to advance for letter-feeding and tabulating, the combination with a letter-feed mechanism adapted under the control of the type keys to feed the carriage proportionally to the width of each character typed in terms of different multiples of a given feed increment, of a tabulating means for the carriage, comprising a member having teeth in a row coarsely spaced corresponding to a given multiple of said feed increment, a stop under urge to move into tabulation-terminating tooth-hold with said member but normally clear thereof, said toothed member and said stop being one on the frame and the other movable by the carriage, latch means to hold said stop normally clear of said teeth, an element movable with the carriage, an element on the frame, one of said elements projectable into range of the other for engagement thereby in the tabulating advance of the carriage, means to project the projectable one of said elements and to free said carriage from the control of the letter-feed mechanism for tabulating advance, means responsive to the tabulating advance of one of said elements against the other to release said latch means, wherefore the tabulating advance of the carriage will be terminated by said stop in cooperation with the coarsely spaced teeth of said member, and means responsive to the tabulating advance of one of said elements against the other to restore with a time delay the carriage to the control of the letter-feed mechanism and to retract said stop with at least the same time delay.

7. In a proportional spacing typewriting machine having type keys, and a carriage impelled to advance for letter-feeding and tabulating, the combination with a letter-feed mechanism adapted under the control of the type keys to feed the carriage proportionally to the width of each character typed in terms of different multiples of a given feed increment, of a tabulating means for the carriage, comprising member having teeth in a row and coarsely spaced corresponding to a given multiple of said feed increment, a stop under urge to move into tabulation-terminating tooth-hold with said member but normally clear thereof, said toothed member and said stop being one on the frame and the other movable by the carriage in the direction in which said row of teeth extend, latch means to hold said stop normally clear of said teeth, an element movable with the carriage, an element on the frame, one of said elements projectable into range of the other for engagement thereby in the tabulating advance of the carriage, means to project the projectable one of said elements and to free said carriage from the control of the letter-feed mechanism for tabulating advance, means responsive to the tabulating advance of one of said elements against the other to release said latch means, wherefore the tabulating advance of the carriage will be terminated by said stop in cooperation with the coarsely spaced teeth of said member, and means responsive to the tabulating advance of one of said elements against the other to restore with a time delay first the carriage to the control of the letter-feed mechanism and then with a further time delay to retract the said stop.

8. In a proportional spacing typewriting machine having type keys, and a carriage impelled to advance for letter-feeding and tabulating, the combination with a letter-feed mechanism adapted under the control of the type keys to feed the carriage proportionally to the width of each character typed in terms of different multiples of a given feed increment, of a tabulating means for the carriage, comprising a member having teeth in a row and coarsely spaced corresponding to a

given multiple of said feed increment, a stop under urge to move into tabulation-terminating tooth-hold with said member but normally clear thereof, said toothed member and said stop being one on the frame and the other movable by the carriage in the direction in which said row of teeth extend, latch means to hold said stop normally clear of said teeth, an element movable with the carriage, an element on the frame, one of said elements projectable into range of the other for engagement thereby in the tabulating advance of the carriage, means to project the projectable one of said elements and to free said carriage from the control of the letter-feed mechanism for tabulating advance, and means responsive to the tabulating advance of one of said elements against the other to release said latch means, wherefore the tabulating advance of the carriage will be terminated by said stop in cooperation with the coarsely spaced teeth of said member.

9. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop under constant urge to move into tabulation-terminating engagement with the teeth of said member but normally clear thereof, said toothed member and said stop being one on the frame and the other movable by the carriage, latch means to hold said stop normally clear of said row of teeth, an element movable with the carriage, an element on the frame, one of said elements projectable into range with the other for engagement therewith in the tabulating advance of the carriage, means to project the projectable one of said elements and to free said carriage from the control of the letter-feed mechanism for tabulating advance, means responsive to the tabulating advance of one of said elements against the other to release said latch means, wherefore the tabulating advance of the carriage will be terminated by the engagement of said stop in the row of teeth of said member, and means responsive to the tabulating advance of one of said elements against the other to restore with a definite time delay the carriage to the control of the letter-feed mechanism and to retract said stop with at least an equal time delay.

10. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop movable into tabulation-terminating engagement with the teeth of said member but normally clear thereof, said toothed member and said stop being one on said frame and the other movable by the carriage, latch means to hold said stop normally clear of said row of teeth, an element movable with the carriage, an element on the frame, one of said elements projectable into range with the other for engagement therewith in the tabulating advance of the carriage, a tabulator key, a power actuator responsive to an operation of said tabulator key to execute a cyclic operation, means operable by said power actuator to project the projectable one of said elements and to free the carriage from the control of the letter-feed mechanism for tabulating advance, a latch means to detain said operable means automatically upon operation, means responsive to the tabulating advance of one of said elements against the other to release said first latch means and thereby to cause the engagement of said stop in the row of teeth, a power device called into operation incidental to the release of said latch means to execute a cyclic motion, and means operated by said power device to release said second latch means after a first part of the cyclic motion of the device and in further cyclic motion of the device to retract said stop and restore it to the control of said first latch means.

11. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop under constant urge to move into tabulation-terminating engagement with the teeth of said member but normally clear thereof, said toothed member and said stop being one on said frame and the other movable by the carriage, latch means to hold said stop normally clear of said row of teeth, an element movable with the carriage, an element on the frame, one of said elements projectable into range with the other for engagement therewith in the tabulating advance of the carriage, a tabulator key, a power actuator responsive to an operation of said tabulator key to execute a cyclic operation, means operable by said power actuator to project the projectable one of said elements and to free the carriage from the control of the letter-feed mechanism for tabulating advance, a latch means to detain said operable means automatically upon operation, means responsive to the tabulating advance of one of said elements against the other to release said first latch means and thereby to cause the engagement of said stop in the row of teeth, a power device adapted to be called into operation to execute a cyclic motion, means operated by said power device resultant to a first part of its cyclic motion to release said second latch means, and operated resultant to further cyclic motion to retract said stop and thereby to restore it to the control of said first latch means, and means responsive to the tabulating advance of one of said elements against the other to call said power device into operation.

12. In a typewriting machine having type keys, a frame, a carriage impelled to advance for letter-feeding and tabulating, and a letter-feed mechanism normally in control of the carriage and responsive to various type keys to letter-step the carriage; tabulating means for the carriage, comprising a member movable by the carriage and having a row of teeth, a stop on the frame under constant urge to move into tabulation terminating engagement with the teeth of said member but normally clear thereof, latch means to hold said stop normally clear of said row of teeth, tabulation terminating elements supported on the carriage in a row parallel thereto and individually settable transversely thereto, a tabulator key, an element on the frame projectable from an idle to a controlling position in the tabulating path of the set tabulation terminating elements, said frame-supported element mounted for displacement by any of the carriage-supported elements tabulating thereagainst, operating means responsive to said tabulator key to free the carriage from the control of the letter-feed mechanism and to project said projectable element, latch means to detain said operating means automatically upon operation, means responsive to the tabulating displacement of said projectable element by a set tabulation terminating element to release said first latch means and thereby to cause the engagement of said stop in the row of said teeth, and means responsive also to the tabulating displacement of said projectable element to restore with a time delay the carriage to the control of the letter-feed mechanism and to retract said stop.

13. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop movable into tabulation-terminating engagement with the teeth of said member but normally clear thereof, said toothed member and said stop being one on the frame and the other movable by the carriage, a series of tabulation-terminating control elements arranged in a row lengthwise of the carriage, an element projectable from a normal, idle position into tabulation-terminating range with said control elements, said

projectable element and said control elements being oppositely on the frame and the carriage, tabulation-instituting means, means responsive to said tabulation-instituting means to project said projectable element and to free the carriage from the control of the letter-feed mechanism for tabulating advance thereof, and means responsive to the engagement at tabulating advance of any one of said tabulation-terminating control elements with the projected element to cause the engagement of said stop in said row of teeth of said member for terminating the tabulation.

14. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop movable into tabulation-terminating engagement with the teeth of said member but normally clear thereof, said toothed member and said stop being one on the frame and the other movable by the carriage, a series of tabulation-terminating control elements arranged in a row lengthwise of the carriage, an element projectable from a normal, idle position into tabulation-terminating range with said control elements, said projectable element and said control elements being oppositely on the frame and the carriage, tabulation-instituting means, resiliently active means responsive to said tabulation-instituting means to project said projectable element, means responsive to said tabulation-instituting means to free the carriage from the control of the letter-feed mechanism for tabulating advance thereof, and means responsive to the engagement at tabulating advance of any one of said tabulation-terminating control elements with the projected element to cause the engagement of said stop in said row of teeth of said member for terminating the tabulation.

15. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop movable into tabulation-terminating engagement with the teeth of said member but normally clear thereof, said toothed member and said stop being one on the frame and the other movable by the carriage, abutment means for said stop to react against in terminating a tabulation, means to permit rebounding of said stop from said abutment means, a tabulation-terminating control element, and element projectable from a normal, idle position into tabulation-terminating range with said control element, said projectable element and said control element being oppositely on the frame and the carriage, tabulation-instituting means, means responsive to said tabulation-instituting means to project said projectable element, means responsive to said tabulation-instituting means to free the carriage from the control of the letter-feed mechanism for tabulating advance thereof, and means responsive to the engagement at tabulating advance of one of said elements against the other to cause the engagement of said stop in said row of teeth of said member for terminating the tabulation.

16. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop movable into tabulation-terminating engagement with the teeth of said member but normally clear thereof, said toothed member and said stop being one on the frame and the other movable by the carriage, a tabulation-terminating control element, an element projectable from a normal, idle position into tabulation-terminating range with said control element, said projectable element and said con-

control element being oppositely on the frame and the carriage, tabulation-instituting means, resiliently active means responsive to said tabulation-instituting means to project said projectable element, means responsive to said tabulation-instituting means to free the carriage from the control of the letter-feed mechanism for tabulating advance thereof, a normally inactive cyclic means, means responsive to the tabulating advance of one of said elements against the other to engage said stop with said row of teeth and to cause said cyclic means to execute a cyclic motion, and means actuated by said cyclic means after a first part cyclic motion to cause the withdrawal of said stop from the teeth of said member.

17. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop movable into tabulation-terminating engagement with the teeth of said member but normally clear thereof, said toothed member and said stop being one on the frame and the other movable by the carriage, a tabulation-terminating control element, an element projectable from a normal, id'e position into tabulation-terminating range with said control element, said projectable element and said control element being oppositely on the frame and the carriage, tabulation-instituting means, resiliently active means responsive to said tabulation-instituting means to project said projectable element, means responsive to said tabulation-instituting means to free the carriage from the control of the letter-feed mechanism for tabulating advance thereof, means responsive to the tabulating advance of one of said elements against the other to effect first the engagement of said stop in said row of teeth of said member, thereafter to place the carriage again under the control of the letter-feed mechanism, and finally to withdraw said stop from the teeth of said member.

18. In a typewriting machine having type keys, a carriage impelled to advance for letter-feeding and tabulating, and a letter-feed mechanism normally in control of the carriage and responsive to the various type keys to feed it; tabulating means for the carriage, comprising a member having a row of teeth, a stop movable into tabulation-terminating engagement with the teeth of said member but normally clear thereof, said toothed member and said stop being one on the frame and the other movable by the carriage, an element movable with the carriage, an element on the frame, one of said elements projectable into range with the other for engagement therewith in the tabulating advance of the carriage, one of said elements mounted for displacement by the other during the tabulating advance of the carriage, means to render the projectable one of said elements projected and also to render said carriage free from the control of the letter-feed mechanism for tabulating advance, means responsive to the displacement of one of said elements by the other during the tabulating advance to cause a transitory engagement of said stop in the row of teeth of said member, and means to cause automatically the retraction of the projectable element responsive to said displacement of one element by the other.

19. In a proportional spacing typewriting machine having type keys, and a carriage impelled to advance for letter-feeding and tabulating, the combination with a letter-feed mechanism normally in control of the carriage and operable differentially under the control of the type keys to feed the carriage proportionally to the width of each character typed in terms of different multiples of a given feed increment, of a tabulating means for the carriage, comprising a member having teeth coarsely spaced corresponding to a given multiple of said feed increment, a stop member associated with the toothed member, said toothed member and said stop member

being one on the frame and the other movable by the carriage, said members normally clear of each other and one movable into tabulation-terminating engagement with the other, an element movable by the carriage, an element

5 on the frame, one of said elements projectable into range with the other for engagement therewith in the tabulating advance of the carriage, means to project the projectable one of said elements and to free said carriage from the control of the letter-feed mechanism for tabulating advance, and means automatically responsive to the tabulating advance of one of said elements against the other to engage first said stop member in the row of teeth of the other member and then to restore the carriage to the incremental control of the letter-feed mechanism and to 15 retract said stop member.

20. In a typewriting machine having a letter-feeding carriage capable of occupying finely varying positions, a tabulating means for said carriage including a control mechanism conditionable to terminate the tabulations

20 automatically, said control mechanism comprising elements arranged in a row and individually settable to define different tabulating stations, a control part projectable transversely of said row of elements into cooperative range of the set elements, spring means urging said part

25 into said cooperative range and a member having normally a position to hold said part against projection and being operable to cause projection of said part by said spring means, said member and said part having a saddle and rider association adapted to guide said part normally

30 for projection in a defined path transversely of said row of elements, said saddle and rider association being of a form to lend said part capacity for some deviation in the direction of said row of stops from said normally defined path in the event said part at operation of said member

35 becomes retarded in its projection by striking a set element in its path.

21. In a typewriting machine having type keys, a letter-feeding carriage, and letter-feed mechanism normally in control of the carriage and responsive to the various type

40 keys to feed it; tabulating means for the carriage, comprising a member having a row of teeth, a stop member associated with said toothed member, said toothed member and said stop member being one on the frame and the other movable by the carriage, said members normally clear of each other and one movable into tabulation-terminating engagement with the other, an element

45 movable by the carriage, an element on the frame, one of said elements projectable into range with the other for engagement therewith in the tabulating advance of the carriage, release means operable to free the carriage from the control of the letter-feed mechanism for tabulating advance, means to project the projectable one of said

50 elements and to operate said release means, means automatically effective to detain the projectable element projected and to hold said release means operated, and means responsive to the tabulating advance of one of said elements against the other to engage first said stop member in the row of teeth of the other member, then with a time delay to release said detaining means and finally to

55 60 retract said stop member.

22. In a typewriting machine having a frame, a carriage and means to impel the carriage to advance for letter-feeding and tabulating, the combination with a letter-feed mechanism for control of the carriage and operable

65 differentially to feed the carriage proportionally to the width of each character typed in terms of different multiples of a definite feed increment, of tabulating means for the carriage comprising a row of evenly spaced tabulation terminating teeth, stop means for tabulation terminating

70 cooperation with said teeth, said teeth and said stop means associated with the frame and the carriage so that carriage movement enforces relative movement between said teeth and said stop means congruent to the row of said teeth, tabulation terminating control elements ar-

75 ranged along a line, an element related for cooperation

with said control elements, said control elements and said related element normally out of cooperative range and associated with the frame and the carriage so that movement of the carriage enforces relative movement therebetween congruent to said line, the teeth of said row spaced in accord with the relative movement which is enforced between them and said stop means by a carriage movement of a particular multiple of said increment, and the said control elements arranged along said line, spaced in terms of the movement effected between them and the related element by movement of the carriage to the extent of said particular multiple of said increment, tabulation instituting means, and means responsive to said last means to project said related element relatively to said control elements into tabulation controlling range therewith and additionally to free the carriage from the control of said letter-feed mechanism for tabulating advance, means automatically responsive to the relative encounter at tabulating advance of the carriage of any of said control elements with said related element to project said stop means relatively to said teeth to effect a meshed relation therebetween for terminating the tabulating advance of the carriage, and means independent of the tabulation instituting means to effect thereafter automatically a retraction relatively between said stop means and the teeth of said row, as well as a restoration of the control of the letter-feed mechanism over the carriage.

23. In a typewriting machine having a frame, a carriage and means to impel the carriage to advance for letter-feeding and tabulating, the combination with a letter-feed mechanism for control of the carriage and operable differentially to feed the carriage proportionally to the width of each character typed in terms of different multiples of a definite feed increment, of tabulating means for the carriage comprising a row of evenly spaced tabulation terminating teeth, stop means for tabulation terminating cooperation with said teeth, said teeth and said stop means associated with the frame and the carriage so that carriage movement enforces relative movement between said teeth and said stop means congruent to the row of said teeth, tabulation terminating control elements arranged along a line, an element related for cooperation with said control elements, said control elements and said related element normally out of cooperative range and associated with the frame and the carriage so that movement of the carriage enforces relative movement therebetween congruent to said line, the teeth of said row spaced in accord with the relative movement which is enforced between them and said stop means by a carriage movement of a particular multiple of said increment, and the said control elements arranged along said line, spaced in terms of the movement effected between them and the related element by movement of the carriage to the extent of said particular multiple of said increment, tabulation instituting means, means responsive to said last means to project said related element relatively to said control elements into tabulation controlling range therewith and additionally to free the carriage from the control of said letter-feed mechanism for tabulating advance, and means automatically responsive to the encounter at tabulating advance of the carriage of any of said control elements relatively with said related element, first to project said stop means relatively to said teeth to effect a meshed relation therebetween for terminating the tabulating advance of the carriage, then with a time delay to restore the control of the letter-feed mechanism over the carriage and with at least an equal time delay to effect a retraction relatively between said stop means and the teeth of said row.

24. In a typewriting machine having a frame, a carriage and means to impel the carriage to advance for letter-feeding and tabulating, the combination with a letter-feed mechanism for control of the carriage, of tabulating means for the carriage comprising a row of evenly spaced tabulation terminating teeth, stop means

for tabulation terminating cooperation with said teeth, said teeth and said stop means associated with the frame and the carriage so that carriage movement enforces relative movement between said teeth and said stop means 5 congruent to the row of said teeth, tabulation terminating control elements arranged along a line, an element related for cooperation with said control elements, said control elements and said related element normally out of cooperative range and associated with the frame and 10 the carriage so that movement of the carriage enforces relative movement therebetween congruent to said line, tabulation instituting means, means responsive to said last means to project said related element relatively to said control elements, into tabulation controlling range 15 therewith and additionally to free the carriage from the control of said letter-feed mechanism for tabulating advance, and means automatically responsive to the encounter at tabulating advance of the carriage of any of said control elements relatively with said related element, 20 first to project said stop means relatively to said teeth to effect a meshed relation therebetween for terminating the tabulating advance of the carriage, then with a time delay to restore the control of the letter-feed mechanism over the carriage and with at least an equal time delay 25 to effect a retraction relatively between said stop means and the teeth of said row, the automatically responsive means including power operated timing means to restore the control of the letter-feed mechanism and to effect the retraction relatively between said stop means and 30 the teeth of said row.

25. In a typewriting machine having a frame, a carriage and means to impel the carriage to advance for letter-feeding and tabulating, the combination with a letter-feed mechanism for control of the carriage and operable differentially to feed the carriage proportionally to the width of each character typed in terms of different multiples of a definite feed increment, of tabulating means for the carriage comprising a row of evenly spaced tabulation terminating teeth, stop means for tabulation terminating cooperation with said teeth, said teeth and said stop means associated with the frame and the carriage so that carriage movement enforces relative movement between said teeth and said stop means congruent to the row of said teeth, tabulation terminating 35 control elements arranged along a line, an element related for cooperation with said control elements, said control elements and said related element normally out of cooperative range and associated with the frame and the carriage so that movement of the carriage enforces relative 40 movement therebetween congruent to said line, the teeth of said row spaced in accord with the relative movement which is enforced between them and said stop means by a carriage movement of a particular multiple of said increment, and the said control elements arranged 45 along said line, spaced in terms of the movement effected between them and the related element by movement of the carriage to the extent of said particular multiple of said increment, and means to project said related element relatively to said control elements into tabulation 50 controlling range therewith.

26. In a typewriter or like machine having a frame, and a carriage mounted thereon for letter spacing and return travel; letter spacing mechanism including primary carriage positioning means for effecting carriage letter spacing travel in accord with relatively small increments and thereby establishing new incremental positions of the carriage; secondary carriage positioning means, ineffective upon said carriage during said incremental letter spacing travels of said carriage but adapted to be rendered 55 effective to arrest the carriage in any one of many positions which are coarsely separated in terms of multiples of said increments; a tabulating position defining element; an element adapted to be brought into cooperative relation relatively to the said first element for encounter 60 therewith during tabulating travel of the carriage in ap-

proach of a given one of said coarsely separated positions; means to disable said primary carriage positioning means and cause tabulating movement of the carriage, and additionally to bring said elements into cooperative relation; and means responsive to said encounter of said elements to render said secondary carriage positioning means effective to arrest the carriage as said given one of said coarsely separated carriage positions is reached.
